DESK TRAY

Robert R. Nielsen, 2316 New Orleans St.,
Mount Pleasant, S.C.

Filed Jan. 24, 1963, Ser. No. 73,296

Term of patent 14 years

(Cl. D74—1)

Fig. 1

Fig. 2

Fig. 3

Fig. 4

Fig. 5

Fig. 6

Fig. 7

FIG. 1 is a top perspective view of a desk tray showing my new design;

FIG. 2 is a plan view of the desk tray of FIG. 1;

FIG. 3 is a vertical sectional view taken along line 3—3 of FIG. 2;

FIG. 4 is a front elevational view of the desk tray of FIG. 1;

FIG. 5 is a rear elevational view of the desk tray of FIG. 1;

FIG. 6 is a right-hand side elevational view of the desk tray of FIG. 1; and

FIG. 7 is a left-hand side elevational view of the desk tray of FIG. 1.

I claim:

The ornamental design for a desk tray, as shown.
